(57) **CLAIM**

The ornamental design for a tail light, as shown and described.

DESCRIPTION

FIG. 1 is a front left elevated perspective view of a tail light, showing our design.

FIG. 2 is a front left perspective view thereof.

FIG. 3 is a rear right elevated perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another front view of the tail light shown in FIGS. 1-10, with the tail light mounted on a vehicle and the rest of the vehicle shown in de-emphasized and half-tone portions so as to illustrate environmental structure, which portions form no part of the claimed design. More particularly, in FIG. 11, the inventive tail light is shown within the broken line, and the elements shown outside the broken line form no part of the claimed design, but are instead included to show environmental aspects thereof.

A second embodiment includes the mirror image of the headlamp shown in FIGS. 1-11.
